UNITED STATES PATENT OFFICE.

OLLIE T. NELSON, OF SEATTLE, WASHINGTON.

BOILER.

1,205,473.

Specification of Letters Patent. Patented Nov. 21, 1916.

Application filed August 10, 1915. Serial No. 44,763.

To all whom it may concern:

Be it known that I, OLLIE T. NELSON, a citizen of the United States, and a resident of Seattle, in the county of King and State of Washington, have invented certain new and useful Improvements in Boilers, of which the following is a full, true, and exact specification.

My invention relates to improvements in boilers and has for its principal object, to provide an improved and novel sectional water leg boiler setting for use with my improved tubular boiler as set forth in my application No. 843,985, filed July 8th, 1914.

A further object is to provide a setting to which the boiler need not be secured. Other objects are to provide an improved connection joint between the boiler and setting; to provide a water cooled bridge in the said setting. Applicant has devised a boiler setting which is built in sections in a shop and which is easily transported, carried through limited spaces and quickly set up. Upon this setting the boiler referred to is rested without fastening, an improved circulation connection being maintained by the weight of the boiler. The boiler is now completely set up. The ease and cheapness of assembly and the particular adaptability of the setting to applicant's boiler are important factors in the case.

Other objects will appear as my invention is more fully explained in the following specification, illustrated in the accompanying drawings and pointed out in the appended claims.

Figure 1 is a side elevation of the boiler and setting assembled with parts broken away. Fig. 2 is an enlarged fragmentary elevation and section on line $\alpha-\alpha$ of Fig. 1.

Referring more particularly to the drawings, numeral 1 indicates a boiler similar to my boiler as set forth in my previous application above referred to and having a diametrically offset portion 2. The setting includes an ash pit section 3 and a double construction pressure resisting fire box section 4. The plates of said fire box are stay bolted as at 5 and has all welded seams, thereby being adapted to hold water. A bridge 6 may be built of double construction and integral with the sides of the section so as to be water cooled. The fire box section 4 rests freely upon the ash pit section. The fire box section is rectangular in shape and has a semicircular cut out portion as at 7 in the

front which fits snugly the periphery of the boiled 1, the horizontal diameter of the boiler just closing the top opening of the setting and the offset portion 2 resting upon the straight rear portion 8 of the setting. A water connection between the setting and the boiler is made where the offset portion 2 rests upon the rear portion 8 of the setting. The said connection includes a concave ring 9 welded to the inside of the top plate 8 and around an opening 10 in said plate. A short nipple 11 is secured into the ring 9 and allowed to project above the plate 8. Before the boiler is placed upon the setting, a copper tubular packing ring 12 is placed around the nipple 11 adjacent the concaved portion of the ring 9. A hole 13 is left in the boiler through which the nipple 11 projects. The weight of the boiler compresses the packing 12 and thus makes a tight joint. To facilitate the compression of the packing bolts 14 are welded into the top of the setting and project through lugs 15 on the boiler. By setting up the nuts 16 on the bolts 14, the boiler and setting are drawn together tightly. The compactness of my setting and ease of assembly together with its heat conserving properties should be apparent to all and have proved efficient and satisfactory in actual practice.

While I have shown a particular form of embodiment of my invention, I am aware that many minor changes therein will readily suggest themselves to others skilled in the art without departing from the spirit and scope of the invention, and I therefore desire to avoid being limited to the exact form shown and described except as pointed out in the appended claims.

Having described my invention, what I claim as new and desire to protect by Letters Patent, is—

1. In a water leg boiler setting which is cut away in a semi-circular shape in front and on a horizontal line in the rear and a freely supported boiler with a semi-circular offset in its rear end resting on said setting, the combination of a water connection between the said offset portion of the boiler and the said horizontal portion of the setting, said connection including a concave collar ring secured to the inside of said horizontal portion and positioned opposite an opening therein, a nipple passing through and secured to the ring and a tubular copper packing ring encircling the said nipple.

and resting in the concave portion of the collar, whereby when an opening in the offset portion of the boiler is positioned around the said nipple the weight of the boiler compresses the copper ring and forms a water tight joint.

2. In a connection between a boiler and a water leg boiler setting, the combination of a concave collar ring secured to the inner side of the said setting and concentric with an opening in said setting, a tubular nipple

secured in the opening in the said collar and projecting through an opening in said boiler, and an endless tubular copper packing ring encircling the said nipple and resting in the concave portion of said collar, whereby the weight of the boiler compresses the said copper packing ring between the collar and the boiler and forms a water tight joint between said boiler and setting. 15 20

OLLIE T. NELSON.
